UNITED STATES PATENT OFFICE.

EWALD GLAESEL, OF MARKNEUKIRCHEN, GERMANY.

TUNING-PEG FOR MUSICAL STRING INSTRUMENTS.

1,083,736.

Specification of Letters Patent.

Patented Jan. 6, 1914.

Application filed May 15, 1913. Serial No. 767,787.

To all whom it may concern:

Be it known that I, EWALD GLAESEL, a subject of the German Emperor, and a resident of Markneukirchen, Saxony, Germany, have 5 invented new and useful Improvements in Tuning-Pegs for Musical String Instruments, of which the following is a specification.

The invention relates to improvements of 10 the mechanism on string instruments, by means of which the axle (around which the string is to be wound) and the cog-wheel of a screw and wheel gear can be connected or disconnected by moving or shifting a tap in 15 or out of a recess of the cog-wheel. The disconnection of the cog-wheel and axle enables the axle to be turned without the screw and gear. This is of great advantage in case 20 a string is to be renewed, as it would be tiresome to wind the string all the way by the gear.

In the accompanying drawing a form of construction is shown in Figure 1 in a top view. Fig. 2 shows a side view of the mechanism. Fig. 3 shows in side view a cross-section of a detail of the mechanism enlarged 25 and Fig. 4 shows a top view of another form of construction enlarged.

The mechanism consists of the plate *f*, 30 through which the axle *a* is guided. A cog-wheel *b* is loose (not fixed) mounted upon the axle. A screw or spiral-wheel *e* engages with the cog-wheel. The axle *a* has on its one end *a*¹, which is of smaller diameter a 35 head or button *c*, which can slide upon this part *a*¹ and which can be shifted along this axle *a*¹. This head or button is provided with a U-formed pin *d*, the middle part of which slides in the groove *a*² of the axle *a*¹. 40 This pin can be moved into a recess *b*¹, of the cog-wheel *b* when the head is moved in

the direction of the cog-wheel. A flange *i* is rigidly connected with the axle and arranged in the middle of said groove. This flange has a recess *i*¹ opposite of the recess *b*¹. 45

In the form of construction shown in Fig. 4 the cog-wheel *b* is loosely mounted on axle *a* but it has sidewise a collar bearing *b*² turnably mounted in the plate *f*.

The mode of operation is the following: 50 In case a string on the instrument is to be renewed, the cog-wheel and the axle is disconnected by drawing back the head or button *a* with its fixed pin *d*, which latter leaves the recess *b*¹ of the cog-wheel *b*, thereby entering in the recess *i*¹ and thus enabling the axle *a* to be turned without the gear. 55

I claim:

In a musical string winding mechanism the combination of a plate (*f*) having a 60 series of pivot-holes, a series of string winding axles (*a*, *a*¹) pivoted in said holes, said axles having longitudinal grooves (*a*²), a series of flanges (*i*) each of them being rigidly connected with one of said axles (*a*, *a*¹) 65 and being arranged in the middle of said groove, said flanges having at their sides a radial recess *i*¹, a head (*c*) slidably mounted at the one end of said axle, a U-formed 70 pin (*d*) being rigidly connected at one end with said head, its middle part sliding in said groove (*a*²) and its free end protruding out of said groove, a cog wheel engaging with a screw (*e*) loosely mounted upon said 75 axle and having at one side a recess (*b*¹) adapted for the reception of the protruding free end of said pin (*d*).

EWALD GLAESEL.
